WALTER P. BUTLER, OF ABERDEEN, SOUTH DAKOTA.

PAPER-GAGE FOR TYPE-WRITERS.

1,181,503.

Specification of Letters Patent.

Patented May 2, 1916.

Application filed November 20, 1915. Serial No. 62,630.

To all whom it may concern:

Be it known that I, WALTER P. BUTLER, a citizen of the United States, residing at Aberdeen, in the county of Brown, in the 5 State of South Dakota, having invented a new, novel, and useful Device to be Used as a Paper-Gage for Type-Writers, of which the following is a specification, and to declare as follows.

10 My invention relates to an improvement in a paper-gage to enable the operator of a typewriter to determine, 1st—when he or she arrives at the last or bottom line to be written on a sheet of paper of any length 15 on which a bottom margin of any desired width has been allowed for; also, 2d—to enable the operator to see at a glance how many more lines remain to be written on the page; thus saving time and paper and securing 20 greater neatness and uniformity in the writing to be done. I attain these objects by the mechanism illustrated in the accompanying drawings in which similar letters refer to similar parts throughout the several views 25 which are described as follows.

In the drawings Figure 1, is a front elevation of my invention. Fig. 2, is a side-view of the hook or paper-stop. Fig. 3, is 30 a cross-section of the gage-plate. Fig. 4, is a cross-section through a part of my invention. Fig. 5, is a front-view of my invention showing a rack-and-pinion arrangement for adjusting the gage-plate. Fig. 6, is a front-view of the gage-plate removed from 35 the frame or face-plate. Fig. 7, shows the hinge for attaching the device to the paper-slide or paper-table of the typewriter. Fig. 8, is a cross-section of the device through the 40 rack and pinion. Fig. 9, is an end-view of the device showing its method of folding. Fig. 10, is a front-view of the device showing 45 an alternative method of attachment. Fig. 11, shows the device as attached to the paper-slide or paper-table and folding forward out of use. Fig. 12, is a partial front-view of the device showing its use with a half-length sheet of writing paper. Fig. 50 13, is a partial front-view of the device showing its use with "letter-head" sheets of writing paper. Fig. 14, is a partial front-view of the device showing its use with 55 "legal-cap" sheet of writing paper. Fig. 15, shows a form of hinge to be used in attaching the device to the paper-slide or paper-table of an L. C. Smith typewriter.

Fig. 16, shows an end-view of the hinge shown in Fig. 15. Fig. 17, shows a front-view of the gage-plate with triple row of graduations for "single", "double", and "triple" writing. Fig. 18, shows a front-view of an alternative method of constructing the device. Fig. 19, shows a partial front-view of the device in use to show the relation between the paper being written on and the scales and graduations on the 60 gage-plate. 65

Fig. 1 is a front view of the paper-gage device which is intended to be made as an integral part of a typewriter or added as an attachment thereto (preferably to the metal 70 plate over which the paper slides back of the platen or roller; though it might, in some cases, be more conveniently attached to some other part of the machine). The device consists essentially of two main parts, 75 the face or front plates or frame A A which is to be made of steel, aluminum, or other suitable metal, joined at the back by the metal guide plate B; and the vertically or longitudinally sliding gage-plate C whereon 80 are proper graduations to indicate the line position of the paper.

The gage-plate C slides in the grooves between the front plates A A and the back-plate B of the frame, as shown in Fig. 4, 85 which is a section of the device along the line y y of Fig. 1. The gage-plate C may preferably have a cross section, as shown in Fig. 3, the raised or thicker middle portion adding to the strength of the plate and 90 bringing the graduated face thereof flush with the surface of the face-plate or frame A A. At the upper end of the gage-plate C the metal of which it is made is bent forward to form a hook or stop (see side view 95 of said hook in Fig. 2) against which the top of the paper hits when the last or bottom line to be written is reached.

The graduations on the gage-plate C are in two columns marked S and D. Column 100 S shows the graduations to be used when "single space" writing is used; the numbers 2—4—6, &c., indicating the number of the lines from the bottom or last line to be written. Column D shows the graduations to be used 105 when "double-space" writing is to be used, the numbers 2—3—4, &c., as in the former case, indicating the line-position of the paper with reference to the last or bottom line to be written. The lower set of gradu- 110

ations upon the gage-plate C are for similar use, when but half-length sheets of paper are used.

On the bottom edge of the frame or face-
5 plates A A the metal thereof is rolled over to form a hinge, or a suitable hinge may be thereto attached, through which passes the hinge-rod or pin D. (The form of the hinge, and the method of attachment of this
10 device to a typewriter, may vary widely with the style or design of the various machines and does not constitute an essential feature of this invention.)

Fig. 5 shows an alternative form of this
15 device which is essentially the same as that shown in Fig. 1, except that instead of having the vertical or longitudinal adjustment of the gage-plate C made directly by the hand, there is added to the back of the de-
20 vice a rack and pinion so that by turning the thumb-screw T the gage-plate C is vertically or longitudinally moved and adjusted to the desired position.

Fig. 8 shows, on an enlarged scale, a cross-
25 section of the device along the line v v of Fig. 5. In this view T is the thumb-screw on the outer end of the short shaft running through the bearing U attached to the back-
30 plate B. W is a pinion or star-wheel on the inner end of the said short shaft. It passes through a hole or slit in the back-
35 plate B and engages with or into holes R forming a rack along or in the edge of the gage-plate C, as more clearly shown in Fig.
40 6 which is a front view of the gage-plate C. (The form and arrangement of the rack and pinion, or even its use at all, as an integral part of the device, is not claimed as an essential part of this invention but only as an alternative means of more easily adjusting the gage-plate C.)

Fig. 7 shows a form of hinge which may preferably be used to attach this device to the paper-guide plate of a typewriter. A
45 double row of holes S S and S' S' admit of some vertical adjustment of the device upon the attaching screws or bolts N N; and the horizontal elongation of the said holes admits of some lateral adjustment of the device upon the attaching screws or bolts N N and the paper-guide plate P. (See Fig. 9.)

Fig. 9 is a partial side view of the device A B as attached by a hinge H and bolts N to the paper-guide plate P of a typewriter.
50 If the device A B turns on the hinge at D in the direction of the arrow t until it rests upon the hinge H it is in proper position for use. When not in use the device may be turned in the opposite direction, as indicated by the arrow t' (forward toward the operator). It then rests upon or over the platen Q, thus being out of the way when the cover is placed over the typewriter, or when the machine is folded downward or depressed into a typewriter desk.

Fig. 10 shows the device in position to use and as hinged upon a wire D clamped upon or over the edges of the paper-guide plate P of a typewriter by means of the thumb-screw and clamp at F.

Fig. 11 shows the device turned forward and down over the platen when not in use, and shows the back of the device with the rack and pinion adjusting device, and also the attachment by the adjustable hinge H 75 to the paper-guide plate P.

A second sheet of drawings submitted herewith shows more fully this device in operation and certain modifications thereof. On this sheet Fig. 12 shows the device with the gage-plate C pressed downward to the limit in the frame A thus being in position to use with a short or half-length sheet of paper, which is shown by the dotted line 1 1. The upper edge of the paper having reached the 1 position on the lower scale the operator knows at a glance that the last or bottom line is being written on the sheet.

Fig. 13 shows the device adjusted for use with a regular "letterhead" size sheet of paper. In this case the gage-plate C has been moved up so that when the last or bottom line to be written is in position for writing the upper edge of the paper 2-2 just touches the top of the gage-plate C under the hook or stop E.

Fig. 14 shows the device adjusted for use with a long or "legal-cap" sheet of paper. In this case the gage-plate C is drawn up and out still more so that when the last or bottom line to be written is in position for writing, the upper edge of the paper 3-3 just touches the top of the gage-plate C under the hook or stop E.

Fig. 15 shows a slight modification of the form of the hinge H, such as would probably be used in attaching the device to an L. C. Smith typewriter whereon the paper-guide plate P is curved. In this case a part of the metal of the hinge H is cut and curved or bent upward, as at V, to form a rest or support for the device when turned into position to use.

Fig. 16 is an end view of the device thus attached with the hinge shown in Fig. 15 to the curved paper-guide plate of an L. C. Smith typewriter and clearly shows how the upturned portion V of the hinge H forms a back-rest or support for the frame A-B of the device. Thus may the form of the hinge vary with the varying designs of the many machines to which the device is to be attached so that, as heretofore stated, the form of the hinge-attachment does not enter into the merit of this invention.

Fig. 17 shows an alternative method of graduating the guide-plate C, whereon the left-hand column, and the middle column are graduated respectively for "single-space" and for "two-space" or "double-

space" writing, as shown in all the other views. But there is added thereto a third column, at the right, to be used for "three space" writing. Thus without either physical or mental effort, this device is always in adjustment for any spacing of the lines to be written on the paper.

Fig. 18 shows an alternative design or method of construction of this paper-gage device which is, in principle, the same as the forms shown in the previously numbered views. In this case the face-plate or frame A—A is made of one piece of metal the arms of which are joined at the back by the guide-plate B, as in the former designs. Instead, however, of being attached to the paper-guide plate P by some form of hinge, as heretofore shown, which would permit of the device, when not in use, being folded forward on or over the platen, this form of the device is attached to the paper-guide plate P by some suitable form of screw or bolt, *a*, with washer, *b*, and it is to be held in the vertical working-position shown by any suitable form of clamp or locking mechanism, best suited to the design or contour of the plate P to which it is to be attached; such mechanism not being shown in this view. When not in use the device may be rotated or hinged upon the attaching screw or bolt, *a*, in the lateral direction of the arrow, *d*, (or in the opposite direction) into the horizontal position indicated by the dotted line *c*, when it would lie in a plane parallel with and adjacent to the paper-guide plate P.

Fig. 19 shows how the device appears in use, a sheet of paper lying over the face of the device with all the writing plainly in view. The operator sees at a glance that the upper edge of the paper is on the 13th line of the single-space column of the scale, and on the 7th line of the double-space column of the scale, and he therefore knows at once that he is writing on those respectively numbered lines, as measured from the last or bottom line to be written on that sheet. When the paper has, in the progress of the work, advanced to the position shown by the dotted line 4—4 the operator sees at once that he is then writing on the third line from the bottom (single space), and has but two more lines to write on that sheet; or that he is then writing on the second line from the bottom (double space), and has but one more line to write on the sheet.

Thus simple is the operation of this de-

vice which performs no mechanical function but does—visually—give to the operator 60 the desired information as to the line position of the paper being written upon.

To use this device, it having been attached to the typewriter in any manner best suited to the design or pattern of the machine, 65 mark on the sheet of paper to be used the position of the last or bottom line to be written on the sheet thus allowing for a blank margin of any desired width on the bottom of the sheet. Then insert the sheet 70 in the typewriter and bring the last or bottom line so marked to the position of writing. Then, either with the fingers or by means of the rack-and-pinion attachment, 75 adjust the vertical or longitudinal position of the sliding gage-plate C so that the top edge of the paper just touches the notch under the hook E, as shown in Figs. 13 and 14. The device is thus set for use. Then when writing, as the paper advances upward over the face of the device the upper edge of the paper indicates on the scale on the gage-plate C the number of the line from the bottom of the page which is then being written on, and the number of lines 80 still to be written on that page, as shown in Fig. 19. A great advantage secured by the use of this device is that it holds the paper up so that all the writing thereon is visible instead of allowing the paper to hang down 85 back of the machine where much of the writing is not visible.

Having thus described my invention what I claim as new and novel and useful, and desire to secure by Letters Patent is—

A line-gage mounted on the paper-table of a typewriter and movable as a whole pivotally from an inoperative position below the top of the typewriter carriage to a position upwardly and in rear of and in the same plane with the paper-table, comprising a frame provided with a pair of longitudinal grooves, a metal strip slidably mounted in said grooves, the upper end of the metal strip being bent over forwardly and downwardly, and a line-gage numbered from the top downwardly so mounted upon the strip that the strip may be set so that in line-spacing the indicating numeral on the gage exposed above the leading edge of the sheet 110 will indicate the number of printing lines from the end of the sheet.

WALTER P. BUTLER.
